FIG. 1 is a perspective view of an atomizer according to an embodiment of our design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is a perspective view of an atomizer shown according to another embodiment;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is an enlarged top plan view thereof;

FIG. 16 is an enlarged bottom plan view thereof;

FIG. 17 is a perspective view of an atomizer shown according to further another embodiment;

FIG. 18 is another perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is an enlarged top plan view thereof;

FIG. 24 is an enlarged bottom plan view thereof;

FIG. 25 is a perspective view of an atomizer shown according to further another embodiment;

FIG. 26 is another perspective view thereof;

FIG. 27 is a front elevational view thereof;

FIG. 28 is a rear elevational view thereof;

FIG. 29 is a left side elevational view thereof;

FIG. 30 is a right side elevational view thereof;

FIG. 31 is an enlarged top plan view thereof;

(Continued)

FIG. 32 is an enlarged bottom plan view thereof;
 FIG. 33 is a perspective view of an atomizer shown according to further another embodiment;
 FIG. 34 is another perspective view thereof;
 FIG. 35 is a front elevational view thereof;
 FIG. 36 is a rear elevational view thereof;
 FIG. 37 is a left side elevational view thereof;
 FIG. 38 is a right side elevational view thereof;
 FIG. 39 is an enlarged top plan view thereof;
 FIG. 40 is an enlarged bottom plan view thereof;
 FIG. 41 is a perspective view of an atomizer shown according to further another embodiment;
 FIG. 42 is another perspective view thereof;
 FIG. 43 is a front elevational view thereof;
 FIG. 44 is a rear elevational view thereof;
 FIG. 45 is a left side elevational view thereof;
 FIG. 46 is a right side elevational view thereof;
 FIG. 47 is an enlarged top plan view thereof; and,
 FIG. 48 is an enlarged bottom plan view thereof.
 The broken lines in the drawings depict portions of the atomizer that form no part of the claimed design.
